UNITED STATES PATENT OFFICE.

WILLIAM C. DILLON, OF FORT DODGE, IOWA, ASSIGNOR TO DILLON BANK PROTECTION SERVICE, A CORPORATION.

COMBINED ELECTRICAL AND MECHANICAL SAFETY LOCK FOR VAULT DOORS.

Application filed September 30, 1920. Serial No. 413,799.

The object of my invention is to provide a combined electrical and mechanical safety lock for vault doors, which device is of simple and inexpensive construction and adapted to 5 automatically lock a vault door when the ordinary combination is interfered with, and also adapted to sound an alarm when the safety lock is moved to operative position. My present invention may be used in combination with the type of safety locks shown in my co-pending application, Serial Number 357,658, filed February 10th, 1920.

With these and other objects in view, my invention consists in the construction, arrangement and combination of the various parts of my device, whereby the objects contemplated are attained, as hereinafter more fully set forth, pointed out in my claim, and illustrated in the accompanying drawings, 20 in which:

Figure 1 shows an elevation of the interior of a vault door equipped with a combined electrical and mechanical safety lock, embodying my invention.

Figure 2 shows a detail, sectional view taken on the line 2—2 of Figure 1.

Figure 3 shows a detail, sectional view of the supporting shaft and the safety lock thereon.

Figure 4 shows a similar view of a slightly modified form of my device.

Figure 5 shows a detail, sectional view illustrating the mounting of a slightly modified form of my device on the door.

Figure 6 shows an elevation of the interior of the vault door, equipped with my device.

Figure 7 shows a detail, sectional view of a portion of the electrical equipment.

Figure 8 shows a detail, sectional view 40 taken on the line 8—8 of Figure 7; and

Figure 9 shows a diagram of the electrical circuit.

In the accompanying drawings, I have used the reference numeral 10 to indicate 45 generally the door of a vault or safe. The door has the bar or inwardly extending flange 11 spaced from its edges. The locking bolts 12 are slidably mounted in the bar 11 and are fixed to an upright strip 13.

I have shown the ordinary combination lock 14, from which projects the locking bolt 15 adapted to coact with the locking mechanism 16 ordinarily found on such a door.

My improved device includes a shaft 17 55 preferably screw-threaded for the greater

portion of its length, as shown. One end of the shaft 17 is secured to the bar 11, preferably by screwing it into a suitable hole in the said bar. A lock nut 18 is preferably mounted on the shaft 17 adjacent to the bar 11, and another lock nut 19 may be mounted 65 on the other end of the shaft 17, on the end of the bar 11, as illustrated in the form shown in Figure 5, if desired.

Mounted on the shaft 17 is a safety lock 20, which is preferably screw-threaded, so 70 that it can be rotated on the shaft 17 and also adjusted longitudinally thereof. Lock nuts 21 and 22 are preferably mounted on the shaft 17 on opposite sides of the safety lock 20.

In Figure 4, I have shown a safety lock 23, similar in form to the lock 20, with the exception that the hole 24 therethrough is larger and not screw-threaded.

Where the form of the lock, as shown at 80 23, is employed, the lock nuts 21 and 22 are used, as illustrated in Figure 4.

Mounted in the shaft 17 is an arm or rod 25 on which are lock nuts 26 and 27 on opposite sides of the shaft 17. The arm or rod 85 25 extends away from the shaft 17 at right angles thereto and has at its outer end, a laterally flattened extension 28 arranged substantially parallel with the shaft 17, and provided with a series of holes 29.

Selectively received in one of the holes 29 is one end of the strong coil spring 30. The other end of the coil spring 30 is extended through one of a plurality of holes 31 in the safety lock 20 or 23, as the case may be, as 95 illustrated particularly in Figure 2.

The tension of the spring 30 tends to hold the safety lock 20 in its position illustrated by dotted lines in Figure 2, where it stands in the path of travel of the strip 13. In 100 order to hold the safety lock 20 in its position, shown in full lines in Figure 2, where it will be out of the way of the strip 13, for permitting the ordinary use of the door and the unlocking of the door for ordinary purposes, 105 I have provided the following means:

Connected with the lock 20 at a point substantially between the center of the shaft 17 and the point where the spring 30 is connected with said lock is a rod or wire or the like 32, which is extended from the lock 20 around a pin 33 mounted on the combination lock 14, and thence toward the free edge of the door 10 to a pin 34 on the bar 110

11, to which latter pin, the member 32 is fastened.

It will be seen that when the member 32 is of the proper length, the safety lock 20 will 5 be held in its position shown in Figure 2, extending downwardly from the shaft 17 against the tension of the spring 30. The rod or wire 32 is secured to the safety lock 20 by projecting a laterally extending end 10 of said rod into a hole in the safety lock. The rod 32 is also pivotally connected with the pin 34.

It will be noted that should the combination box be disturbed from its position by 15 shooting, punching or burning, the rod 32 will be released, whereupon the spring 30 will swing the safety lock 20 from its position shown in Figure 2 in the full lines to its position shown in dotted lines in said 20 figure, where it will stand in the path of the strip 13.

It thus appears that if the vault is locked in the ordinary way, and the combination lock is interfered with, the safety lock 20 will 25 be moved to position for preventing the movement of the strip 13 for releasing the locking bolts 12 from locking position. It would then be impossible to unlock the vault door without releasing the safety lock 20, 30 which practically could not be done by a burglar.

When my locks are installed, a diagram of the door is retained, which makes it possible to determine exactly where the safety 35 lock is located, so that the persons in possession of the proper information can release my safety lock with comparative ease.

As a matter of fact, such releasing is accomplished by drilling through the door and 40 inserting a small tool into the hole 35 in the lock 20, shown by the dotted lines in Figure 1, whereupon the lock 20 may be pulled to position, where it is out of the path of the strip 13, which may then be slid or moved 45 for unlocking the bolts 12.

In connection with my safety lock above described, I have provided an electrical device for indicating that the combination has been tampered with.

50 Mounted on the arm 25 are slightly spaced strips of insulation 36 and 37, between which there is supported a flat spring or the like 38, having an elongated slot 39. On the arm 25 between the insulation strips 36 and 55 37 is an insulating sleeve 40.

Mounted on the shaft 17 is a pin or bolt or the like 41 on which is an insulated sleeve 42. The spring 38 is mounted on the arm 25 and pin 41 with the sleeves 40 and 42 60 received in the slot 39, as illustrated in Figures 1, 7 and 8.

One end of the spring 38 is twisted, as shown at 43, and stands adjacent to the safety lock 20. Connected with the other 65 end of the spring 38 is a current conducting

wire 44. The lock 20 has a contact point 45, which may be a silver screw, which will not corrode, which is so located that when the lock 20 stands in its position illustrated in full lines in Figure 2, the point 45 will be 70 substantially spaced from the spring end 43, but when the lock 20 is moved to its position shown in dotted lines in Figure 2, the point 45 will engage the portion 43 of the spring 38 for causing a circuit through the 75 wire 44, the battery or other source of electrical energy 46, the wire 47, the alarm device 48, the wire 49, the door, the shaft 17 and the lock 20.

The simplicity of my device is obvious 80 from the foregoing description.

It will be seen that the lock 20 is longitudinally adjustable on the shaft 17, which makes it easy to adjust my safety lock device for use with vault doors of different 85 kinds.

By adjusting the lock 20 longitudinally on the shaft 17 it may be moved to proper position for coacting with the strip 13, whatever 90 the width of such strip may be.

By adjusting the end of the spring 38 to different holes 29, the position of such spring may be adjusted to correspond to the adjustment of the safety lock 20.

On account of the use of the spring 38 with the slot 39, it will be seen that by adjusting the pin 41, which preferably has the form of a screw bolt, and the lock nut 50, shown in Figure 1, the spring 38 may be adjusted longitudinally to place it in proper 100 position for coacting with the contact point 45 in any of the adjusted positions of the safety lock 20.

It is obvious that changes may be made in the construction and arrangement of my 105 improved combined electrical and mechanical safety lock for vault doors, without departing from the real spirit and purpose of my invention, and it is my intention to cover by my claim, any modified forms of structure or use of mechanical equivalents, which may be reasonably included within its scope.

I claim as my invention:

A circuit closing mechanism adapted for use on an auxiliary lock having a supporting 115 rod and a locking lug rotatably and longitudinally adjustable thereon, said mechanism comprising bolts extending from said supporting rod, a contact element comprising a strip of metal having a longitudinal 120 slot therein through which said bolts extend, means for allowing longitudinal adjustment of said strip on said bolts whereby said strip may be adjusted longitudinally relative to said supporting rod and a contact element on said lug adapted to coact with said strip when said lug is in one of its adjusted positions.

WILLIAM C. DILLON.
